UNITED STATES PATENT OFFICE.

VERNON DURBIN, OF NEWTON, MASSACHUSETTS, ASSIGNOR TO THE HOLTZER-CABOT ELECTRIC COMPANY, OF ROXBURY, MASSACHUSETTS, A CORPORATION OF MASSACHUSETTS.

ANNUNCIATOR.

Application filed January 5, 1922. Serial No. 527,200.

The present invention relates to an improvement in annunciators.

The object of the invention is to improve and simplify the construction of annunciators in order to reduce the cost of production thereof and in order to increase their efficiency and durability.

To the accomplishment of these objects the improved annunciator of the present invention consists in the structure hereinafter described and particularly pointed out in the claims.

The preferred form of the invention is illustrated in the accompanying drawing in which Fig. 1 is a plan view of the armature; Fig. 2 is a section taken on the line 2—2 Fig. 1 looking in the direction of the arrows; Fig. 3 is a section taken on the line 3—3 Fig. 1; and Fig. 4 is a perspective view.

A target 10 is mounted on a pintle 11. This pintle is pointed at both ends and at the rear end is supported in a depression in a pintle support 12 which is riveted at 13 to the base plate 14. The front end of the target pintle 11 is supported in an indentation in the front pintle support 15 which is formed of non-magnetic metal attached to the pole pieces of two magnets hereinafter described. The pintle 11 carries an armature plate 16 which is substantially semicircular in form having two horns, one at each side. A projection from the center of the armature plate upward forms one support for the target stem 17. The target stem is riveted to the armature plate at two points, one above and the other below the pintle.

The annunciator is provided with two separate electromagnets 20 and 30 both supported from the base plate 14, having cores 40 which are riveted thereto. The forward ends 21 and 31 of the magnet cores support the pole pieces 22 and 32 which are concaved on their sides adjacent to each other on arcs corresponding to the curvature of the armature plate 16. The magnets 20 and 30 are separately energized, the one, as 30, to throw the target into announcing position and the other, as 20, to throw the target into unannouncing position. When the magnet 20 is energized it pulls the armature plate 16 to the position shown in full lines in Fig. 2, thereby throwing the target 10 into announcing position. When the magnet 30 is energized it pulls the armature plate 16 into the

dotted line position shown in Fig. 2, thereby throwing the target into the dotted line position, which is unannouncing position.

The construction commends itself to the manufacturer by reason of the fact that the base plate 14 and the rear pintle support 12 may be made of sheet stampings and riveted together by simple operations; that the magnets 20 and 30 may be separately made and prepared for assembling; that the armature plate and target are made of stampings and easily and cheaply riveted together and easily associated with the pintle; further by reason of the fact that the whole structure with the exception of the target, armature plate and pintle may be assembled by simple operations, the one magnet being riveted to both the base plate and the front pintle support in one operation and the other magnet being riveted to the base plate and front pintle support by another operation, the pole pieces being previously riveted to the front pintle support which holds such pole pieces in proper relation to each other; then the target, pintle and armature plate piece may be inserted by springing back the rear pintle support rearwardly to permit the pintle to be inserted in the depression in the front pintle support and in the depression in the rear pintle support. When thus assembled the structure is rigid and the four wires leading to the magnets may be connected to suitable connectors or leading-in wires.

The annunciator is adapted for use either with direct or alternating current and by reason of the fact that the target overbalances the armature plate when one magnet is energized it will swing the target into its announcing or unannouncing position, in which position it will remain until the other magnet is energized to swing it into unannouncing or announcing position as the case may be.

Having thus described the invention, what is claimed is:

1. An annunciator having, in combination, a base plate, two electromagnets supported on the base plate, a pole piece for each magnet, a front pintle support connecting the pole pieces, a rear pintle support consisting of a spring member attached to the base plate, an armature carrying a target and adapted to turn within the fields of the magnets, and a pintle upon which the armature is mounted, the ends of the pintle being

adapted to be received in the front and rear pintle supports after assembly of all the other parts by reason of the yielding of the rear pintle support longitudinally of the pintle.

2. An annunciator having, in combination, two separately energized electromagnets, a base plate connecting the rear ends of the magnets, a front pintle support connecting

the front ends of the magnets, a rear pintle support consisting of a forwardly bent spring member attached to the base plate and adapted to move longitudinally of the pintle position, and a pintle carrying a segmental armature and a target, the ends of the pintle being received within the pintle supports.

VERNON DURBIN.
